TELEVISION METHOD AND APPARATUS

Henry Haldeman-Julius, Downey, Calif.

Application November 9, 1942, Serial No. 465,019

2 Claims. (Cl. 178—6)

This invention relates to a system of television, and it has for its object to provide method and apparatus for producing images by television at a distant point without the necessity of providing any scanning mechanism, such as has usually been necessary in television apparatus.

Broadly stated, the invention contemplates the stimulation of a multiplicity of photo-electric cells, by light rays from the images to be transmitted, the various cells being stimulated to a greater or lesser degree in accordance with the strength or intensity of the light rays striking thereon. Electric currents delivered under the influence of said photo-electric cells to sound emitters or vibrators, of which there are as many as there are photo-electric cells, cause said vibrators to deliver sound waves constituting a multiplicity of tones. These tones, picked up by a microphone, are delivered at a distant point to a radio receiving apparatus having incorporated therein a multiplicity of vibrators responding sympathetically to, and only to, the corresponding vibrators of the sending apparatus.

The actuation of these vibrators sets up a multiplicity of electric currents in wires leading to a corresponding number of lights disposed behind a translucent screen, each light being shielded from its companion lights so that the whole screen, when it is illuminated, will present an image that is a duplicate of the image at the sending station.

Means by which the foregoing objects are accomplished in a simple, efficient and economical way are illustrated in the accompanying drawings, wherein:

Fig. 1 is a view partly in section and partly in side elevation of a camera-like structure which constitutes the viewing element of the scene to be transmitted;

Fig. 2 is a view partly in side elevation and partly in section of a casing containing the sound emitters and microphone receiver, hereinafter described;

Fig. 2a is a modification of Fig. 2;

Fig. 3 is a vertical, sectional view with parts in elevation, showing the radio receiving element at the receiving station, hereinafter described;

Fig. 4 is a front elevation of the structure of Fig. 3;

Fig. 5 is a diagrammatic view illustrating the vibrators and the loud speaker of the structure of Fig. 3;

Fig. 6 is a view partly in edge elevation and partly in vertical section, of the translucent screen and associated lights; and

Fig. 7 is a fragmentary perspective view illustrating the means for shielding the lights from each other.

Like numerals designate corresponding parts throughout the several views of the drawings.

In the drawings, Fig. 1 designates a camera-like viewing device of box-like formation, comprising a body 5. A small opening or a lens 6 is provided through which light rays from the scene to be transmitted, pass to the rear wall of the structure where they impinge upon the photo-electric cells 7. These cells are disposed upon the arc of a circle that is concentric with the center of the lens or the opening 6 and they are preferably so disposed as to constitute an internal segment of a sphere, so that every photo-electric cell will be equi-distant from the center of the lens 6 and so that sharp images may be transmitted. Each cell 7 has its own individual electric wire 8, in which electric currents may be set up, which currents will vary in intensity in proportion to the intensity of the light rays impinging upon the several cells, it being clear that these will vary as the lights and shadows of the images to be televised, vary. The wires 8 lead to a corresponding number of vibrators 9 disposed in such relation to the receiving microphone 10 of a conventional radio broadcasting device that the tones broadcast under control of the microphone 10 will represent a combination of the tones delivered thereto by the vibrators 9. In Fig. 2a a modification of this structure is illustrated, wherein the vibrators 9a are concentrically disposed with relation to the microphone 10a. Thus, each vibrator will deliver the proper volume of tone to the receiving microphone even though they deliver tones of varying quality or pitch. At the receiving station the radio waves broadcast from the sending station are picked up by a conventional type of receiving apparatus 12, by which they are converted into waves of audio frequency and delivered to a standard speaker 13. Vibrators 14 of the character of those illustrated in Fig. 2, are stimulated to varying degrees and in accordance with the composition of the tones delivered from the speaker 13. Electrical conductors leading from the vibrators have currents set up therein which vary in strength under the control of vibrators 14. These conductors lead to light bulbs 15 that are disposed in the rear of a translucent screen 16 upon which the image is to be reproduced. A cell-like structure 17 houses the bulbs 15 to shield them from each other and to prevent the light from one bulb from affecting an area of the

translucent screen 16 that is out of alignment with said bulb. Thus sharp images are secured, it being apparent that the images will be produced by the lights and shadows arising from the fact that some of the bulbs will be only slightly stimulated, others will be highly stimulated and some will not be lighted, at all. It will be seen that by the use of the method and apparatus herein-described, television may be effected without scanning apparatus and sharp images may be had. The capability of the apparatus to produce these sharp images arises in large measure from the fact that all of the photo-electric cells 7 are equi-distant from lens 6, all of the vibrators 9 may be made equi-distant from microphone 10 and every bulb 15 is screened from every other bulb. As far as I am aware I am the first to provide apparatus having these capabilities. Further, the principle of transferring images in space (radio, telephone, etc.) or time (recordings) or both by segregating differential light quantities into gradiated sound impulses of varied intensity and pitch is not to be interpreted as limited to the medium of radio for that sound transference. It is intended to have represented as an example of the several mediums by which all parts of an image may simultaneously be communicated in time and/or space. And it is intended that such pitches or tones and intensities of sound, which establish a relationship between the receiving or reproducing sets, will find use, by themselves or ac-

companying music, voice, or any other kind of sound, in the other ways, such as wire transmission or sound recordings, that sound may be transferred or kept.

- 5 It is to be understood that the invention is not limited to the precise construction shown but that it includes within its purview whatever changes may be fairly made within either the terms or the spirit of the appended claims.
- 10 Having described my invention, what I claim is:
1. In apparatus of the character described, a translucent screen, a bank of lights rearwardly of said screen and a cell-like housing for shielding said lights from each other, a plurality of vibrators, and means for lighting said lights to varying degrees of intensity under the influence of the vibrators, there being an individual vibrator for each of said lights.
- 15 2. The herein-described method of reproducing images at distant points by television which consists of converting light rays from the images to be transmitted to a multiplicity of sound tones which vary in accordance with the lights and shadows, transmitting the composite effect of said tones to a distant station as electrical waves, converting said electrical waves back to a multiplicity of sound tones and illuminating an area with varying degrees of light under the influence of the variations of the sound tones at the receiving station.

HENRY HALDEMAN-JULIUS.
